UNITED STATES PATENT OFFICE.

FRANK T. COPE, OF ALLIANCE, OHIO, ASSIGNOR TO THE ELECTRIC FURNACE COMPANY,
OF ALLIANCE, OHIO, A CORPORATION OF OHIO.

ELECTRIC FURNACE.

1,218,058.

Specification of Letters Patent.

Patented Mar. 6, 1917.

Application filed April 27, 1915. Serial No. 24,232.

To all whom it may concern:

Be it known that I, FRANK T. COPE, a citizen of the United States, residing at Alliance, in the county of Stark and State 5 of Ohio, have invented a new and useful Electric Furnace, of which the following is a specification.

My invention relates to electric furnaces and has more especial reference to the form 10 of electric furnace in which a trough containing a resistance material is located within the heating chamber of the furnace and the objects of the present invention are to provide a furnace of the character referred to in which the resistance trough 15 is so located within the heating chamber that air spaces are provided around the trough allowing the air to circulate around the trough for the purpose of preventing 20 excessive overheating of the same.

A further object is to provide such a furnace which is simple of construction and durable and effective.

With these objects in view the invention 25 consists in the novel construction and arrangement of parts, hereinafter described, illustrated in the accompanying drawings, and particularly pointed out in the appended claim, it being understood that various changes in the form, proportions, size 30 and minor details of construction may be made within the scope of the appended claim, without departing from the spirit or sacrificing any of the advantages of the invention.

In the drawings:

Figure 1 is a transverse sectional view 40 through a furnace constructed in accordance with my invention.

Fig. 2 is a longitudinal section taken on line 2--2, Fig. 1.

Fig. 3 is a transverse sectional view of a slightly different form of furnace.

Similar numerals of reference indicate 45 corresponding parts throughout the several views of the drawings.

Referring more especially to the construction illustrated in the accompanying drawings, the numeral 1 indicates the base of 50 the furnace, said base being made in any suitable form and preferably composed of metal, feet 2 being formed thereon for the

purpose of raising the furnace off of the floor. The heating chamber of the furnace is provided with the hearth 3, side walls 55 4 and 5, end walls 6, and roof 7 all of which are composed of fire brick or similar heat resisting material.

The refractory trough 8, is of the usual construction, being composed of suitable 60 heat resisting material, and contains the granular refractory, resistance material 9, an electrode 10 being embedded within the resistance material near each end of the trough for the purpose of completing an 65 electric circuit through the resistance material.

The refractory trough is supported upon a series of transverse supporting walls 11, 70 said walls being supported upon the hearth, 75 and the trough is spaced away from the side walls and roof so as to allow the air to continually circulate around the trough, preventing excessive heating of the trough upon any one side and causing a more even 75 temperature upon all sides of the trough. In the ordinary forms of electric furnace, such as are at present in use, the refractory trough is located upon the hearth or in contact with one or more of the side walls 80 of the heating chamber, thus preventing the air from circulating entirely around the trough and causing the trough to become excessively heated upon one or more sides instead of evenly distributing the heat around 85 all sides of the trough.

In Figs. 1 and 2 the letter A indicates a plurality of billets which are placed upon the hearth in order to be heated to the proper temperature, the billets being inserted and removed through the door 12 located in the side wall 5 of the heating chamber. These billets are placed beneath the refractory trough and between the supporting walls 11. It will, of course, be understood that in furnaces in which the refractory trough is not of a very great length 90 it will not be necessary to provide the supporting walls 11 for the purpose of supporting the trough as the trough may then 95 be supported at the ends only by means of the end walls 6.

In Fig. 3 is shown a slightly modified 100 form of construction in which the billets

A are adapted to be placed above the trough 8^a instead of beneath the same, the billets being inserted and removed through the door 12^a and resting upon the refractory 5 trough and the wall 5^a. The base 1^a, legs 2^a, bottom wall 3^a and side wall 4^a are all of practically the same construction as the equivalent members in the form shown in Figs. 1 and 2. The trough 8^a may be supported by spaced walls 11^a and the roof 7 in this form of furnace is preferably flat as shown.

Although the drawings and above specification disclose the best mode in which I have contemplated embodying my invention I desire to be not limited to the details of such disclosure, for, in the further practical application of my invention, many changes in form and construction may be made, as circumstances require or experience suggests, without departing from the

spirit of the invention, within the scope of the appended claim.

I claim:

In a resistance furnace, a refractory 25 trough, a granular resistance material contained in said trough and spaced transversely disposed walls for supporting the refractory trough within the heating chamber of the furnace so that the trough is 30 spaced upon all sides from the upper, lower and side walls of the furnace allowing circulation of air transversely around the refractory trough between said spaced walls.

In testimony that I claim the above, I 35 have hereunto subscribed my name in the presence of two witnesses.

FRANK T. COPE.
